UNITED STATES PATENT OFFICE

121,892

DESIGN FOR A COMBINED CALENDAR AND APPOINTMENT INDICATOR

Thomas D. Covert, Meridian, Miss.

Application April 24, 1940, Serial No. 91,923

Term of patent 7 years

To all whom it may concern:

Be it known that I, Thomas D. Covert, a citizen of the United States, residing at Meridian, in the county of Lauderdale and State of Mississippi, have invented a new, original, and ornamental Design for a Combined Calendar and Appointment Indicator, of which the following is a specification, reference being had to the accompanying drawing, forming part thereof.

I claim:

The ornamental design for a combined calendar and appointment indicator, as shown.

THOS. D. COVERT.
